UNITED STATES PATENT OFFICE

DENIS T. MORTON, OF GRAYSVILLE, TENNESSEE

SCAFFOLD

Original application filed December 23, 1927, Serial No. 242,219. Divided and this application filed December 6, 1928. Serial No. 224,243.

This invention relates to a scaffold and more particularly to a scaffold intended for use by bill posters and sign painters, and this application constitutes a division of my co-pending application for a patent upon a scaffold filed December 23, 1927, Serial No. 242,219.

One object of the invention is to provide a scaffold which may be erected in front of a sign board to be painted without obstructing the outer or forward surface of the sign board and thereby be prevented from interfering with the work.

Another object of the invention is to permit the platform of the scaffold to be folded into a compact mass when not in use so that it may be stored in a small space or easily transported from one place to another and to provide the folding platform with a collapsible truss which will very effectively support it when in an extended position but so formed that it will move to a folded position between sections of the platform when the platform is folded.

25 The invention is illustrated in the accompanying drawings, wherein

Figure 1 is a view in front elevation showing the improved scaffold applied to a sign board to be painted,

30 Fig. 2 is an enlarged view showing a portion of the platform in perspective,

Fig. 3 is a transverse sectional view through the platform taken on the line 3—3 of Fig. 1, and

35 Fig. 4 is a longitudinal sectional view through the platform showing the same in a partially folded position.

The platform constituting the subject-matter of this invention forms part of a scaffold to be used when painting a sign board such as shown in Fig. 1 and indicated in general by the numeral 41. This scaffold includes standards 42 constructed as specifically shown in the co-pending application referred to above and adapted to be disposed vertically in front of the sign board and connected with the upper and lower edges thereof. Vertically adjustable carriages 43 are carried by the standards and from these carriages extend brackets 44 to support the im-

proved platform indicated in general by the numeral 45 and upon which workmen stand or sit while painting the sign board.

The platform consists of companion sections 46, each of which includes side bars 47 joined at their outer ends by an end bar 48 and between which extend intermediate bars or strips 49 retained in place by cross rods 50 and held in proper spaced relation to each other by spacing blocks 51. By this arrangement the weight of the platform is greatly reduced but at the same time a workman is provided with a good surface to stand or sit upon. Notches 52 are formed in the side bars 47 adjacent the outer ends of the two platform sections, and these notches are to receive the brackets 44, as shown in Fig. 1, so that the platform will be firmly engaged with the two brackets and there will be no danger of its slipping longitudinally out of engagement with either of the brackets. It will be understood that any number of notches may be provided. At their inner ends the two platform sections carry hinge leaves 53 which consist of metal strips secured against the inner side faces of the side bars 47 and project from the inner ends thereof with their extended ends overlapped and formed with registering openings through which a pivot rod 54 passes. This rod also constitutes means to pivotally mount the side arms 55 of a center strut 56 forming part of a bracing truss for the platform and a sleeve 57 which is preferably a pipe of a suitable length is fitted upon the pivot rod 54 between the arms 55 to retain these arms in proper spaced relation to each other and close against the hinge leaves 53.

The truss which is employed to reinforce the platform and support it in an operative position is of the queen post type and in addition to the center strut 56 also includes end struts 58 which are disposed intermediate the ends of the platform sections. Each of the struts 58 is of an inverted U-shape and consists of a pivot bar 59 journaled in the side bars 47 and carrying side arms 60 connected with the pivot bar by T-couplings 61. The side arms 60 are hollow and preferably formed of strong pipe of a suitable length 100

and each arm slidably receives a plunger 62 having an eye 63 at its outer end which receives a cross rod 64. Set screws 65 pass through threaded openings formed in the arms, and by referring to Fig. 3 it will be seen that each of the plungers is reduced in diameter to provide upper and lower shoulders adapted to engage the inner end portions of the set screws and prevent the plungers from sliding into or out of the arms beyond a desired distance. Therefore, the plungers may slide freely into and out of the arms but they cannot become entirely disconnected from the arms. Truss bars 66 extend between the struts 56 and 58 and have their inner ends pivotally mounted upon the connecting rod 67 joining the lower ends of the arms 55 and have their outer ends pivotally mounted upon the ends of the connecting rods 64 of the struts 58. End bars extend between the struts 58 and the outer end portions of the platform sections and each consists of companion rods or bars 68 and 69 which are slidably connected by sleeves 70 and 71. The sleeves 70 are rigid with the rods 68 and slidably receive the rods 69 and the sleeves 71 are rigid with the rods 69 and slidably receive the rods 68. This is clearly shown in Figs. 2 and 4, and referring to these figures it will be seen that the rods 68 and 69 may slide freely longitudinally of each other but are limited in their movement away from each other by engagement of the sleeves with each other. Turnbuckles 72 are provided so that the truss may be held under proper tension when in an operative position.

When the scaffold is in use, the standards are in front of the sign board, as shown in Fig. 1, in spaced relation to each other and preferably in spaced relation to the ends of the sign board. After the standards have been applied to the sign board, the platform sections are swung to an extended operative position in which they are disposed in end to end relation to each other and the end portions of the platform rest upon the brackets 44 with the brackets received in the notches 52 so that the platform will be firmly engaged with the brackets and prevented from slipping off the same. The workmen stand or sit upon the platform and since the carriages may be vertically adjusted upon the standards all portions of the sign board may be easily reached. When the platform is removed from the brackets and its sections are swung toward a folded position, the plungers 62 move out of the arms 60 of the struts 58 so that the two sections may be swung towards each other until they contact and the struts 58 are disposed longitudinally of the platform sections instead of at right angles thereto. During this movement, the end rods 68 and 69 slide longitudinally of each other, as shown in Fig. 4. It will thus be seen that the platform may be reduced to a compact mass

so that it will occupy a small amount of space and may be easily transported from one place to another. When the platform is in use, the truss is disposed as shown in Figs. 1 and 2, and provides a very strong support which will prevent the platform from collapsing.

Having thus described the invention, I claim:

1. In a scaffold, a platform having companion sections pivotally connected in end to end relation to each other and adapted to be swung from an extended position to a folded position, and a bracing truss for said platform having struts pivoted to the platform and truss rods pivotally connected with the struts, the struts being located one beneath each platform section intermediate its ends and one at the pivotally connected ends of the platform sections, certain of the truss rods extending between the outer end portions of the platform sections and adjacent struts and consisting of inner and outer sections slidably longitudinally of each other and limited in their movement away from each other.

2. In a scaffold, a platform having companion sections pivotally connected in end to end relation to each other and adapted to be swung from an extended position to a folded position with one section resting against the other longitudinally thereof, and a foldable bracing truss for said platform extending longitudinally beneath the same and consisting of struts pivoted to said sections intermediate the ends thereof, a center strut pivotally mounted coincident with the pivotally connected ends of the platform sections, rods extending between and pivotally connected with said struts, and anchor rods having inner sections pivoted to the first-mentioned struts and outer sections pivoted to the platform sections, means being provided to slidably connect the anchor rod sections and limit sliding thereof away from each other when the platform sections are swung to an extended position.

3. In a scaffold, a platform having companion sections pivotally connected in end to end relation to each other and adapted to be swung from an extended position to a folded position with one section resting against the other longitudinally thereof, and a foldable bracing truss for said platform extending longitudinally beneath the same and consisting of struts pivoted to said sections intermediate the ends thereof, a center strut pivotally mounted coincident with the pivotally connected ends of the platform sections, said struts each consisting of depending arms spaced from each other transversely of the platform and the arms of the center strut being of greater length than the arms of the first-mentioned struts, rods extending longitudinally of the platform and having their ends pivotally connected with the lower

ends of the arms of the first-mentioned struts, and anchor rods having inner and outer sections slidably connected and limited in their movement away from each other, the inner sections being pivoted to the first-mentioned struts and the outer sections pivoted to the platform sections.

4. In a scaffold, a platform having companion sections pivotally connected in end to end relation to each other and adapted to be swung from an extended position to a folded position, and a bracing truss for said platform having a center strut pivotally mounted coincident with the connected ends of the platform sections and other struts pivoted to the platform sections intermediate the ends thereof, said struts each consisting of arms spaced from each other transversely of the platform, the arms of the last-mentioned struts having inner sections and outer sections slidable longitudinally thereof, transverse brace rods for the arms of the center strut and outer sections of the arms of the last-mentioned struts, truss rods extending between the struts and having their ends pivoted to the brace rods, and anchor rods having inner sections pivoted to the brace rods of the last-mentioned struts and outer sections slidable longitudinally upon the inner sections and having their outer ends pivoted to the platform sections adjacent the outer ends thereof.

5. In a scaffold, a platform having companion sections pivotally connected in end to end relation to each other and adapted to be swung from an extended position to a folded position, and a foldable bracing truss for said platform disposed beneath the same and including struts pivoted to the platform sections and end and intermediate truss bars pivotally connected with said struts, the end bars consisting of inner and outer sections slidable longitudinally of each other and having their outer ends pivoted to the platform sections adjacent their outer ends.

6. In a scaffold, a platform having companion sections pivotally connected in end to end relation to each other and adapted to be swung from an extended position to a folded position, and a foldable bracing truss for said platform disposed beneath the same and including struts pivoted to the platform sections and end and intermediate truss bars pivotally connected with said struts, the end bars consisting of inner rods pivotally connected with the adjacent struts and outer rods pivoted at their outer ends to the outer end portions of the platform sections and having their other end portions overlapping companion inner rods, the last-mentioned ends of said rods being provided with sleeves slidably receiving companion rods and adapted to contact to limit movement of the rods away from each other.

7. In a scaffold, a platform having companion sections pivotally connected in end to end relation to each other and adapted to be swung from an extended position to a folded position, and a foldable bracing truss for said platform disposed beneath the same and including a center strut pivotally mounted coincident with the pivotally connected ends of the platform sections and end struts pivotally mounted intermediate the ends of the platform sections, said struts each consisting of depending arms spaced from each other transversely of the platform, the arms of the end struts being hollow, a cross rod connecting the lower ends of the arms of said center strut, plungers slidably into and out of the hollow arms of the end struts, cross bars connecting the plungers of each end strut, truss bars extending between the struts and loosely engaged with said cross bars, and end bars having inner sections loosely engaged with the cross bars of the end struts and outer sections slidable longitudinally of the inner sections and pivotally connected with the platform sections.

In testimony whereof I affix my signature.
